[57] **CLAIM**

The ornamental design for handles for drum and pail closing tool, as shown and described.

DESCRIPTION

FIG. 1 is a left front perspective view of handles for drum and pail closing tool in base position, showing my new design;

FIG. 2 is a top plan view thereof;

FIG. 3 is a front elevational view thereof, the rear elevation being a mirror image;

FIG. 4 is a left side elevational view thereof;

FIG. 5 is a right side elevational view thereof;

FIG. 6 is a bottom plan view thereof; and,

FIG. 7 is a rear elevational view thereof in fully open position.

The broken lines in FIG. 1 represent the peripheral multiple jaws of a drum and pail closing tool and form no part of the present design, the jaws being shown merely to illustrate the environment.
